UNITED STATES PATENT OFFICE.

FREDERICK E. HADERMANN, OF NEW YORK, N. Y.

DESIGN FOR A SMOKER STAND.

Application filed October 15, 1921. Serial No. 508,022. Term of patent 3½ years.

To all whom it may concern:

Be it known that I, FREDERICK E. HADERMANN, a citizen of the United States, residing at New York city, in the county of Bronx and State of New York, has invented a new, original, and ornamental Design for Smoker Stand, as shown in the accompanying drawing and described in the following specification.

In the accompanying drawing—

I claim:

The ornamental design for smoker stand as shown and described.

FRED. E. HADERMANN.

Witnesses:

EDW. R. DEANE,
F. J. LORD.
